UNITED STATES PATENT OFFICE.

ISAAC B. ABRAHAM, OF NEWPORT NEWS, VIRGINIA.

WEDGE-SUPPORTING BLOCK FOR AXLE-BOXES.

1,254,383.

Specification of Letters Patent. Patented Jan. 22, 1918.

Application filed October 8, 1917. Serial No. 195,424.

To all whom it may concern:

Be it known that I, ISAAC B. ABRAHAM, a citizen of the United States, residing at Newport News, in the county of Warwick 5 and State of Virginia, have invented a new and useful Wedge-Supporting Block for Axle-Boxes, of which the following is a specification.

The present invention resides in certain 10 improvements over the wedge supporting block for axle boxes disclosed in my patent #1,133,082, granted March 23, 1916, the function of the block being to support and firmly hold in place, the wedge of a locomotive driving or axle box.

With the ordinary construction, the wedge not infrequently becomes loose, due to the loosening of the bolts holding it, resulting in serious conditions, such as the throwing out 20 of adjustment of the lead and lap of the valve gear and consequent loss of fuel, the jarring of the steam pipes causing leakage, the jarring of the engine and springing of the rivets in the boiler causing leakage, the 25 breakage of steam bolts, the throwing of the drive wheels out of line causing undue wear on the wheel flanges, and other well known objections. By the provision of the present device, the wedge is prevented from being 30 accidentally loosened in a simple, yet thoroughly efficient and practical manner, without entailing any alterations or prohibitive expense in the driving box construction.

The invention has for a further object, the 35 provision of a wedge supporting block which can be readily increased in thickness to take up wear as the wedge is adjusted for that purpose, such increase in thickness of the block being readily accomplished by the 40 insertion of one or more shims, the parts of the block being held together by means of pins which need not be renewed or replaced, as in the patented device, as the block is increased in thickness.

With the foregoing and other objects in view, which will appear as the description proceeds, the invention resides in the combination and arrangement of parts and in the 45 details of construction hereinafter described 50 and claimed, it being understood that changes in the precise embodiment of the

invention can be made within the scope of what is claimed without departing from the spirit of the invention.

The invention is illustrated in the accompanying drawing, wherein:

Figure 1 is a side elevation of the driving or axle box frame showing the block disposed under the wedge.

Fig. 2 is an enlarged sectional view on the line 2—2 of Fig. 1.

Fig. 3 is a sectional view on the line 3—3 of Fig. 2.

The usual driving box frame is shown in the drawing consisting of the upper and lower braces 5 and 6, respectively, the pedestal legs 7 and 8 between them, and a pedestal cap or binder 9 bolted, as at 10, to the lower brace 6. A shoe 11 is fastened to the leg 7, 70 and the wedge 12 fits the leg 8, being provided with side flanges 13 overlapping the opposite sides of the leg 8, so that the wedge straddles said leg. The wedge is provided at its lower larger end with a T-shaped groove 75 14 extending transversely therethrough for the reception of the head 15 at the upper end of a vertical wedge adjusting bolt 16 that extends downwardly through the binder 9 of the frame and through an underlying tongue or bracket 17 carried by the binder. 80 Nuts 18 are threaded on the bolt 16 above and below the tongue 17 for adjusting said bolt to raise and lower the wedge and hold it in any adjusted position. These nuts commonly become loose, however, due to the vibration and flow of lubricant from the driving box to said nuts, so that the wedge becomes displaced, resulting in the above mentioned and other objections.

The wedge supporting block is designated generally by the numeral 20, and has the same general function as the block disclosed in said patent—that of firmly supporting the wedge 12 in its adjusted position, and preventing the loosening thereof. 90 This block 20 is disposed underneath the wedge above the binder 9 of the frame, to be clamped between the larger lower end of the wedge and binder.

The block 20 is composed of upper and lower plate-like sections 21 and 22 parallel with one another and having their remote or

opposite faces roughened or toothed throughout, as at 23 and 24, respectively, whereby the upper teeth 23 of the section 21 bite the lower end of the wedge, while the lower teeth 24 of the section 22 bite the binder or frame member 9, when the block is clamped between the wedge and binder, thus firmly holding the block in place against accidental displacement. The block 10 20 is of greater length than the width of the binder 9, so that the ends of the block project beyond and overhang the sides of the binder, as seen in Fig. 2, giving room for the means which hold the parts of the 15 block assembled, as will hereinafter more fully appear. To increase the thickness of the block, as the wedge 12 is raised, to take up wear, one or more shims or spacer plates 25 of the same outline as the block sections 20 25 are disposed or sandwiched between the sections of the block. The shims 25 are added from time to time, to increase the thickness of the block as the wedge is raised, and said shims can be readily added and removed as 25 needed.

In order to hold the block sections and shims in position against relative misplacement, the block section 21, block section 22 and shims 25 are provided with the respective apertures 26, 27 and 28 at their ends and in vertical alinement, the apertures 26 being of larger diameter than the others. Pins 29 are inserted through said apertures, thereby preventing the parts of the blocks from 30 shifting relatively, and said pins have heads 30 at their upper ends fitting within the apertures 26 and seating on the uppermost shim 25, to support said pins. The pins 29 can be of sufficient length to extend through 35 the parts of the block when it is of maximum thickness, and when the block is of less thickness the pins 29 can depend from the block at the opposite sides of the binder 9, as seen in Fig. 2, said pins being raised as 40 the block is increased in thickness. Thus, the two pins 29 will suffice for all thicknesses of the block. The sections and shims of the block are provided between their ends with laterally opening recesses 31 fac- 45 ing the pedestal leg 8 for the reception of the bolt 16, thereby permitting the block to be readily moved into place toward the leg 8 under the wedge. The parts of the block are of extremely hard metal to resist any 50 compression or shrinkage, and to also avoid wear on the teeth, so that the teeth will effectively bite the wedge and frame due to the pressure of the wedge on the block.

Having thus described the invention, what 60 is claimed as new is:

1. In an axle box construction, a wedge supporting block having a wedge bolt receiving recess.
2. In an axle box construction, a wedge 65 supporting block comprising sections and a

shim therebetween, said sections and shim having wedge bolt receiving recesses.

3. The combination with an axle box frame, a wear adjusting wedge fitting it, and an adjusting bolt connected to the wedge, of 70 a wedge supporting block between the wedge and frame having a recess to accommodate said bolt.

4. The combination with an axle box frame, a wear adjusting wedge fitting it, 75 and means between the wedge and frame for adjusting the wedge, of a wedge supporting block between the wedge and frame having a recess for accommodating said means.

5. The combination with an axle box 80 frame, a wear adjusting wedge fitting it, and adjusting means between the wedge and frame, of a wedge supporting block between the wedge and frame comprising sections and a shim therebetween, the sections and 85 shim each having a recess for accommodat- ing said means.

6. The combination with an axle box frame, a wear adjusting wedge fitting it, and a wedge adjusting bolt, of a wedge supporting block between the wedge and frame, comprising sections and a shim therebetween, 90 said sections and shim each having a recess for accommodating said bolt.

7. In an axle box construction, a sectional 95 wedge supporting block, and detachable retaining means extending from one section beyond the other to accommodate different thicknesses of the block.

8. In an axle box construction, a wedge 100 supporting block adapted to be increased in thickness, and detachable retaining means for the block in all of its thicknesses from the minimum to the maximum.

9. In an axle box construction, a wedge 105 supporting block comprising sections, means to be disposed therebetween for varying the thickness of the block, and detachable retaining means for the parts of the block and arranged to accommodate all thicknesses 110 thereof.

10. In an axle box construction, a wedge supporting block comprising sections, means disposable between the sections for varying the thickness of the block, and detachable retaining means extending from one section beyond the other for holding the parts of the block relatively in position and accom- modating all thicknesses of the block.

11. In an axle box construction, a wedge 120 supporting block of sectional construction to increase its thickness, and a detachable retaining pin extending through the block beyond the same for accommodating all thicknesses thereof.

12. In an axle box construction, a wedge supporting block of sectional construction to increase its thickness, a detachable retaining pin extending through the block beyond the same for accommodating all 130

- thicknesses thereof, and means for supporting the pin.
13. In an axle box construction, a wedge supporting block of sectional construction to increase its thickness, and a retaining pin extending through the block beyond the same for accommodating all thicknesses thereof, the pin having a head seatable in the block for supporting it.
14. In an axle box construction, a wedge supporting block comprising sections, means disposable therebetween for varying the thickness of the block, said sections and means having apertures, and means insertible in said apertures and projectable from one section to retain the parts in place in the various thicknesses of the block.
15. In an axle box construction, a wedge supporting block comprising sections, a shim therebetween, said sections and shim having alining apertures, and a pin insertible through said apertures and beyond one block section for accommodating all thicknesses of the block.
16. In an axle box construction, a wedge supporting block comprising sections, a shim therebetween, said sections and shim having alining apertures, and a pin insertible through said apertures and beyond one block section for accommodating all thicknesses of the block, the aperture of one block section being larger than the others and the pin having a head in said larger aperture.
17. In an axle box construction, an adjustable wedge supporting block comprising sections, and detachable retaining means at the opposite ends thereof for holding the sections in relative position in all thicknesses of the block.
18. In an axle box construction, an adjustable wedge supporting block comprising sections, and retaining means at the opposite ends thereof for holding the sections in relative position in all thicknesses of the block, the block having a wedge bolt receiving recess between its ends.
19. In an axle box construction, a wedge supporting block comprising sections, means disposable therebetween to increase the thickness of the block, and pins insertible through the block for holding the sections thereof in relative position and located at the ends of the block.
20. In an axle box construction, a wedge supporting block comprising sections, means disposable therebetween to increase the thickness of the block, and pins insertible through the block for holding the sections
- thereof in relative position and located at the ends of the block, said pins projecting from the block opposite to the wedge engaging face to accommodate all thicknesses of the block.
21. In an axle box construction, a wedge supporting block comprising wedge and frame engaging sections, means disposable therebetween for varying the thickness of the block, said sections and means having alining apertures at their ends, and pins insertible through said apertures and projecting beyond the frame engaging section, the apertures of the wedge engaging section being larger than the others, and the pins having heads in said larger apertures.
22. The combination with an axle box frame and wedge fitting it, of an adjustable wedge supporting block between the wedge and frame and formed of sections, and retaining means for the sections of the block extending therefrom at one side of the frame to accommodate all thicknesses of the block.
23. The combination with an axle box frame and wedge fitting it, of a wedge supporting block between the wedge and frame comprising sections, means disposable between the sections for increasing the thickness of the block, and pins supported by and extending through the parts of the block and extending therefrom at opposite sides of the frame to accommodate all thicknesses of the block.
24. The combination with an axle box frame, a wedge fitting it, and a wedge adjusting means, of a wedge supporting block between the wedge and frame engaging sections, a shim between the sections, said sections and shim each having a recess to accommodate said means, the sections and shim having alining apertures at their ends, and pins inserted through said apertures and projecting beyond the frame engaging section at the opposite side of the frame for accommodating different thicknesses of the block, the wedge engaging section having larger apertures than the others, and the pins having heads in said larger apertures.

In testimony that I claim the foregoing as my own, I have hereto affixed my signature in the presence of two witnesses.
